(57) **CLAIM**

The ornamental design for an electric door for LED panel fixture, as shown and described.

DESCRIPTION

FIG. 1 is an enlarged front elevational view of the electric door for LED panel fixture showing my new design;

FIG. 2 is a perspective view thereof;

FIG. 3 is a reduced perspective view thereof; and,

FIG. 4 is a reduced perspective view thereof.

The broken line illustration of an LED panel fixture shown in FIGS. 3 and 4 illustrate environmental structure and form no part of the claimed design.

1 Claim, 4 Drawing Sheets

FIG. 1

FIG. 2

FIG. 3

FIG. 4
